TOY AIRPLANE

Philip K. McGall, Orange, N. J.

Application November 2, 1935, Serial No. 48,020

5 Claims. (Cl. 46—76)

This invention relates to improvements in toy airplanes of the glider type, which are adapted to be projected into the air to relatively great heights by a suitable catapult or similar device.

5 It is an object of the invention to provide a toy glider which has the appearance of a real airplane, especially in mid-air, and is light, strong and compact. A further object is to produce a toy of this nature which is foldable and partially 10 demountable to facilitate packing and shipping.

These and other objects will appear from the following description, taken in connection with the drawings, which show a preferred embodiment of the invention.

15 Referring to the drawings:

Figure 1 is a plan view of a toy airplane embodying the present invention.

Figure 2 is a side elevation of the toy shown in Fig. 1;

20 Figure 3 is a cross-section and partial end elevation of the wings taken on line 3—3 of Figure 1;

Figure 4 is a fragmentary longitudinal cross-section and side elevation of one of the wings taken on line 4—4 of Figure 1;

25 Figure 5 is a cross-section and end elevation of the stabilizing and guide vanes taken on line 5—5 of Figure 1;

Figures 6, 7, 8, and 9 are perspective views of 30 certain details employed in the construction of the toy which constitute part of the present invention;

Figures 10 and 11 are perspective views of the stabilizing and guide vanes respectively;

35 Figure 12 is a perspective view of the launching device for projecting the toy into the air;

Figure 13 is a perspective view illustrating the manner of projecting the device into the air; and

40 Figure 14 is a perspective view of the toy as it appears when folded and demounted and partially inserted in a packing box or shipping container.

Referring more particularly to the drawings, the body of the toy comprises a square bar or 45 stick 10 preferably made of wood or some light weight material. A pair of wings 11 and 12 are pivotally mounted on bar 10 adjacent its front end but spaced therefrom, while the vanes 13 and 14 for guiding the toy in its flight are mounted on the rear portion of bar 10, vane 13 constituting a stabilizing vane and vane 14 acting as a 50 guide vane. Wings 11 and 12 are permanently attached to body 10 by means of a strong wire 55 staple 15 having a pair of arms 16 and 17 which

constitute vertical pivots about which the wings may be rotated or swung in a substantially horizontal plane. Arms 16 and 17 pass through suitable apertures provided in the rear corners of wings 11 and 12 adjacent bar 10, as well as corresponding apertures 18 and 19 in the flanges 20 and 21 of a bent sheet metal plate 22 (see Fig. 8). These flanges act as means for guiding the position and movement of wings 11 and 12 during rotation or oscillation thereof and serve to prevent any substantial movement or rotation of the wings about a horizontal axis. Plate 22 is provided with a centrally bent or folded portion 23 which may be fitted or sprung into a longitudinal slot 24 provided in bar 10 near its front portion. 15 This slot extends downwardly a substantial distance from the top of bar 10 but not completely therethrough. In order to attach the plate and wings substantially permanently to bar 10, arms 16 and 17 of staple 15 are made of sufficient 20 length to provide prongs 25 and 26 which extend below the lower edges of body 10 and are bent upwardly and forced into the wood of bar 10. An arrangement of this nature is of great 25 advantage, since the wings 11 and 12 may be swung back or folded preparatory to launching the device into the air and the toy may be projected to far greater heights than would otherwise be possible. The provision of foldable wings also facilitates quick and easy packing and 30 storing of the toy.

Wings 11 and 12 are also provided with metal 35 clips 27 and 28 extending partially along the edges 29 and 30 which contact plate 22 when the wings are in extended position. These clips are compressed about edges 29 and 30 and serve to protect them and prevent wear between the moving and contacting parts. They may be provided with stamped out portions, such as shown at 31 in Figure 6, which bite into the wood of the 40 wings and insure a firm grip. Clips 27 and 28 are also each provided with apertures, such as indicated at 32 in Figure 6, which are placed in alignment with the apertures in the associated wings 11 and 12 and permit the staple arms 16 and 17 45 to be passed therethrough.

The central folded portion 23 of plate 22 is cut out at one end to provide a narrower portion 33 which extends beyond slot 24 and rests on a cross bar 34 which rests in turn upon bar 10 and prevents wear on the upper surface thereof. This cross-bar is also provided with apertures 35 and 36 for receiving arms 16 and 17 of staple 15. 50

Suitable spring means, such as elastic bands 37 and 38 are provided for retaining the wings in 55

spread-out or sidewardly extending position. These bands are fastened to a hook 39 which extends in a horizontal direction longitudinally of bar 10 and centrally of plate 22 and is provided with a downwardly extending portion 40. Portion 40 passes down along the front end of slot 24 and terminates in a prong 41 which is driven diagonally into the body 10 to retain hook 39 firmly in place. The other ends of the elastic bands 37 and 38 are fastened to the wings by any suitable means, such as fine wire staples 42 and 43, which are so positioned that when the wings are retracted manually as far as possible with vane 14 in place, the bands still exert a forward pull thereon. In other words, staples 42 and 43 are fastened at such a position on the wings that even when the wings are fully retracted, the bands 37 and 38 do not coincide with or pass over the imaginary lines connecting hook 39 with arms 16 and 17 respectively, which constitute the centers of rotation of the wings. Thus, the wings are normally retained by the elastic bands in unfolded or spread-out condition, and must be moved manually to their rearward position and be manually retained in such position. Moreover, flanges 20 and 21 on plate 22 are spaced sufficiently from the top surface of bar 10 so that there is room for slight play upwardly and downwardly of the wings between bar 10 and flanges 18 and 19. This arrangement permits elastic bands 37 and 38 to hold wings 11 and 12 in such a manner that the wings form a dihedral angle of less than 180° with the wing tips 44 and 45 slightly raised, which facilitates the effective gliding and operation of the toy.

A suitable bolt or rivet 46 is inserted in the extreme front portion of bar 10, and is sufficiently long to extend entirely through bar 10 and out beyond the same so as to provide a suitable projection for receiving the elastic band or similar device 47 of a catapult or launching device 48. Bolt 46 extends through bar 10 at an angle to the vertical, so that its projecting portion is slightly farther away from the front portion of bar 10 than the body of bolt 46. This tends to prevent accidental disengagement of the elastic element of the catapult and renders the bolt less easy to loosen or remove.

Vanes 13 and 14 are mounted in the rear end 50 of bar 10 by inserting them in suitable slots 49 and 50. Vane 13 may be firmly retained in slot 49, as by glue or any other means, and is positioned at a slight angle to the horizontal with its rear end uppermost, so that it assumes a positive angle of incidence to the air in the direction of travel, which fosters the gliding action of the toy during use. Vane 13 is also provided with a centrally located slot 51 near its front portion which is in alignment with the vertical slot 50 in bar 10. Slot 51 is relatively short, being made of such length as to snugly receive the finger or extension 52 on vane 14. Thus, vane 14 is held in place in slots 50 and 51 by a friction fit, is prevented from withdrawal in a rearward and downward direction by the fixed vane 13, and may be easily separated from the body of the toy by a simple upward lifting thereof. Finger 52 not only serves as a wedge to hold the vane firmly in position, but also extends a small distance out beyond the body and thereby acts as or assumes the appearance of a tail-skid.

In using the device, wings 11 and 12 are swung back or folded together until the outer ends 44 and 45 contact vane 14. The toy is then supported in one hand by grasping the body and

wings between the thumb and fore-finger, and the elastic element 47 of a suitable launching device, such as catapult 48, is placed in engagement with bolt 46 and the toy is thereby projected upwardly into the air. The resistance of the air tends to keep the wings in their folded position until the toy loses speed near the top of its travel. At this time the wings snap together, and the airplane gradually glides to the earth while assuming a variety of movements, such as turning, diving, or floating along in a substantially horizontal direction.

In Figure 14 the device is shown in its folded condition with the vane 14 removed, and the parts, including the catapult 48 partially inserted 15 in a suitable shipping carton or container 53.

The toy is made of few parts, is simple in construction, relatively strong, and may be propelled by the force of the catapult to relatively great heights without undue deviation by virtue of the 20 folding capacity of the wings and their tendency, when folded, to guide the device in a straight path. The gliding action of the toy is greatly facilitated by providing the wings with a dihedral angle of less than 180° as well as by mounting 25 the stabilizing vane so that it assumes a positive angle of incidence to the air in the direction of movement. The toy has an appearance similar to an airplane when in mid-air, and tends to glide to earth in a variety of ways which is very pleasing- 30 to the eye.

It is to be understood that the drawings merely show a preferred form of the invention, and that the benefit of all equivalents to the means and elements hereinbefore described are to be included within its scope.

I claim:

1. A toy airplane comprising a body member, a plurality of pivoted wings, elastic elements for yieldably retaining the wings in extended position and simultaneously holding them at a dihedral angle of less than 180°, the wings being higher at their tips than at their central portions, and means for stabilizing and guiding the device.

2. A toy airplane comprising a body member, 45 a pair of foldable wings, elastic elements for yieldably retaining the wings in unfolded condition, and simultaneously maintaining the wings at a dihedral angle of less than 180°, the tips of the wings being raised with respect to the body member, a stabilizing vane, and a guide vane, the stabilizing vane being mounted at an acute angle to the horizontal.

3. A toy airplane comprising a body member, a plurality of movable wings, the wings being restricted to movement in a substantially horizontal plane, elastic elements for yieldably retaining the wings in extended position and simultaneously holding them at a dihedral angle of less than 180°, and means for stabilizing the device.

4. A toy airplane comprising a body member, a plurality of wings, a stabilizing vane and a removable guide vane, the guide vane having a depending portion which is adapted to be snugly received in a slot in the body member and extends completely through and below the body member thereby forming a tail skid.

5. A toy airplane comprising an elongated body, a plurality of wings pivotally mounted on the body and capable of being folded to facilitate launching, said wings being restricted to movement in a horizontal plane, means for yieldably retaining the wings in extended position, and means for guiding the device.
